CLAIM

The ornamental design for an oropharyngeal tube with nares occluder, substantially as shown and described.

DESCRIPTION

FIG. 1 is a front perspective view of an oropharyngeal tube with nares occluder showing my new design.

FIG. 2 is a side elevational view thereof, as viewed from the right hand side of FIG. 1.

FIG. 3 is a rear elevational view thereof.

FIG. 4 is top plan view thereof.

FIG. 5 is a front elevational view thereof.

FIG. 6 is a bottom plan view thereof.
